DESIGN FOR A RUBBING BLOCK

Lucchesi J. Feild, Detroit, Mich.

Application October 19, 1937, Serial No. 72,313

Term of patent 14 years

To all whom it may concern:

Be it known that I, Lucchesi J. Feild, a citizen of the United States, residing at Detroit, county of Wayne, in the State of Michigan, have invented a new, original, and ornamental Design for a Rubbing Block, of which the following is a specification, reference being made to the accompanying drawing, forming part thereof, in which:

Fig. 1 is a side view, in perspective, of a rubbing block embodying my new design.

Fig. 2 is a top view thereof.
Fig. 3 is a side elevation thereof.
Fig. 4 is an end view thereof.

I claim:

The ornamental design for a rubbing block as shown.

LUCCHESI J. FEILD.
